UNITED STATES PATENT OFFICE.

ALBERT S. HURSH, OF MILTON, PENNSYLVANIA.

FOLDING BASKET.

1,071,054.

Specification of Letters Patent.

Patented Aug. 26, 1913.

Application filed June 22, 1910. Serial No. 568,321.

To all whom it may concern:

Be it known that I, ALBERT S. HURSH, a citizen of the United States, and a resident of the city of Milton, county of Northumberland, and State of Pennsylvania, have invented certain new and useful Improvements in Folding Baskets, of which the following is a specification.

My invention relates to improvements in folding baskets, the object of the invention being to provide a basket which can be readily folded into small space, and yet, which when given sufficient jerk while holding onto the handle, will open and remain open for use.

A further object is to provide improvements of this character of extremely simple inexpensive construction, which can be quickly and easily manipulated either to open or to fold, and which are strong and durable in use.

With these and other objects in view, the invention consists in certain novel features of construction and combinations and arrangements of parts, as will be more fully hereinafter described and pointed out in the claims.

In the accompanying drawings: Figure 1, is a view in side elevation illustrating my improved basket in its open position. Fig. 2, is a view in longitudinal section. Fig. 3, is a perspective view of the bail and handle. Fig. 4, is a view in longitudinal section of the basket folded. Fig. 5, is a top plan view of the basket with the bail removed, and Fig. 6, is a view in cross section.

The basket is made with a shallow box-like bottom 1, the end walls 2 of which being slightly higher than the side walls 3.

40 4, 4, represent the sides of the basket, and 5, 5, the ends. The sides and the ends are connected with the walls 2, and 3, by means of rods 6, which project through sleeves 7 on the sides, ends and walls, the sleeves 7 being 45 formed by tongues on the edges of the several parts bent upon themselves, the sleeves of the sides and ends being in alignment with the sleeves of the walls, affording a hinged connection between the sides, ends 50 and walls, when the rods 6 are in position.

Coiled springs 8 are positioned on the rods 6 connecting the ends 5 with the end walls 2, and one end of each spring bears against the end 5, while the other end of the spring 55 bears against the end wall 2, and these springs exert pressure upon the ends 5, tend-

ing always to press them inwardly and downwardly into the position on top of the sides 4, 4, when the latter are folded inwardly as shown in Fig. 4.

Spring catches 9 are secured to the extreme ends of ends 5, project at right angles to the ends 5, are located outside of the sides 4, and are bent between their ends forming lugs 10, which are adapted, when the basket is in open position, to project through openings 11 in the sides 4, limiting the outward movement of the sides as well as the inward movement of the ends, and when the basket is supported by my improved handle, as 60 will hereinafter be explained, the basket will be maintained in its open form ready for use. To each of the sides 4, plates 12 are 65 fixed and carry secure to the sides, metal eyes 13, to receive the hooked ends 14 of my 70 improved bail 15.

The bail 15 comprises two wires or members, both of which are projected through a tubular handle 16, and are looped at their 75 ends as shown at 17, so as to engage around the opposite member and limit the sliding movement of the member through the handle. By reason of this construction of bail, the desired spring tension may be had to insure the box being held in open position, and 80 yet permit it to be folded.

When the basket is folded as illustrated in Fig. 4, and it is desired to use the basket, it is simply necessary to grasp the handle 16, and then with a considerable jar allow the 85 basket to fall or to drop some distance, when the action of the bail 15 will be to swing the sides to vertical position, thus forcing the ends out to vertical position and the spring catches 9 will engage in the openings 90 11, and the basket will be ready for use. To fold the basket, it is simply necessary to release the catches 9, force the sides inward, the ends following by reason of the pressure of the springs 8, when the bail 15 95 may be folded down onto the folded basket, and the device will occupy but very small space.

Various slight changes might be made in the general form and arrangement of parts 100 described without departing from my invention, and hence I do not limit myself to the precise details set forth, but consider myself at liberty to make such changes and alterations as fairly fall within the spirit 105 and scope of the appended claims.

Having thus described my invention,

what I claim as new and desire to secure by Letters Patent is:

1. A folding basket comprising a bottom, sides and ends hinged to said bottom, 5 springs exerting inward pressure on said ends, and a bail comprising a handle and a pair of members telescopically mounted in said handle, the outer ends of said members being connected to said sides respectively, substantially as described.
2. A folding basket comprising a bottom, sides and ends hingedly connected to said bottom, springs exerting inward pressure on said ends, spring catches on said ends, 15 said sides having openings into which said catches engage when the device is in open position, said ends adapted to fold inwardly on top of said sides, and a bail fixed to said sides whereby a sharp pull on the bail will 20 expand said basket, substantially as described.
3. A folding basket comprising a bottom, sides and ends hinged to said bottom, ver-

tically disposed elongated eyes on said sides, and a bail comprising a handle and a pair 25 of members each having an end telescoping within said handle and the opposite ends connected to said eyes, substantially as described.

4. A folding basket comprising a bottom, 30 sides and ends hingedly connected to said bottom, said ends adapted to fold inwardly on top of said sides, springs exerting inward pressure on said ends to normally hold said sides and ends in folded position, and a bail 35 connected at its ends to said sides, whereby a sharp upward pull on said bail will unfold said sides and said ends to expand said basket, substantially as described.

In testimony whereof I have signed my 40 name to this specification in the presence of two subscribing witnesses.

ALBERT S. HURSH.
